UNITED STATES PATENT OFFICE

MAXWELL W. REH, OF NEW YORK, N. Y.

DESIGN FOR A CANDELABRA

Application filed May 23, 1932. Serial No. 43,874. Term of patent 7 years.

To all whom it may concern:

Be it known that I, MAXWELL W. REH, a citizen of the United States, and a resident of the city of New York, borough of Bronx, in the county of New York and State of New York, have invented the new, original, and ornamental Design for a Candelabra, of which the following is a specification.

I claim:

The ornamental design for a candelabra substantially as shown.

MAXWELL W. REH.
